MANIFOLDING DEVICE FOR AUTOGRAPHIC REGISTERS.

1,133,816.

Specification of Letters Patent. Patented Mar. 30, 1915.

Application filed July 3, 1912. Serial No. 707,410.

To all whom it may concern:

Be it known that we, FREDERICK C. NICKOL and MILTON C. STERN, citizens of the United States, residing at Dayton, in the county of Montgomery and State of Ohio, have invented certain new and useful Improvements in Manifolding Devices for Autographic Registers, of which the following is a specification, reference being had therein to the accompanying drawing.

This invention relates to manifolding devices and is in the nature of an improvement upon the device shown and described in Patent No. 1,015,581, granted to us January 23rd, 1912.

The object of the invention is to render the operation of the machine more positive and more accurate and to hold the paper more securely against accidental displacement.

To this end it is a further object of the invention to so construct the paper gripping device, which forms a part of the paper-feeding mechanism, that it will grip the paper at the end of the rearward movement of the feeding device, thus holding the paper against displacement while the same is being written upon; to provide paper gripping devices which will be automatically moved into engagement with the paper to hold the same against displacement during the rearward movement of the paper feeding devices, and which will be automatically actuated to release the paper to permit the same to move with the paper feeding devices when the latter are moved forward or in a direction away from the writing table; to provide means for regulating the length of movement of the paper feeding devices to accommodate them to bills or checks of different lengths and to variations of the check or bill from the prescribed length; to provide an operating handle, the operation of which will be automatically reversed to drive the feeding mechanism in either direction; and further, to provide an automatic lock to hold the spindles or shafts for the rolls normally against longitudinal movement.

It is also an object of the invention to provide a machine embodying these several features, the construction of which will be simple and of a mechanical nature, thereby

providing a strong, durable machine, the parts of which will not be readily disarranged.

In the accompanying drawings, Figure 1 is a side elevation, partially in section, of an autographic register embodying our invention; Fig. 2 is a front elevation of the same partially broken away; Fig. 3 is a horizontal section taken on the line $\alpha\alpha$ of Fig. 1 and looking in the direction of the arrows; Fig. 4 is a side elevation of the forward portion of the register showing the paper feeding device in its extended position; Fig. 5 is a plan view of a portion of the paper gripping devices, supported on the frame adjacent to the writing table; Fig. 6 is a detail view of the tripping mechanism for releasing the paper gripping device of Fig. 4; Fig. 7 is a detail view of the reversible operating handle; Fig. 8 is a detail of the lock for the cover; Fig. 9 is a longitudinal sectional view of the forward part of the machine showing the controlling means for the feeding device; Fig. 10 is a perspective view of one of the forward corners of the machine showing this same device; and Fig. 11 is a longitudinal sectional view of the machine showing the writing table tilted.

In these drawings we have illustrated one embodiment of our invention and have shown the same as applied to an autographic register of a known type, the main features of construction of which are well known and need not be described in detail. The machine as a whole comprises a frame consisting of side members 1 mounted on a base 2 and connected by suitable rods or tie bars.

A flat top portion 3 is hinged to the frame near the forward end thereof and constitutes the support for the paper while a record is being made upon the latter, or, in the usual form of the machine, a writing table. The paper upon which the record is made is usually supported beneath the writing table or paper support upon rolls 4 carried by shafts 5 which are removably mounted in the side members 1 of the frame to enable the rollers to be placed in position or removed. The webs of paper are carried rearward from the respective rolls about guide rollers 6 in the upper portions of the frame members near the rear ends thereof and thence extend forward over the paper sup-

- port or writing table 3 to the paper feeding carriage which will be hereinafter described. A protecting plate or cover 7 is movably mounted on the main frame and rests normally upon the paper, covering the same with the exception of that portion thereof which is to receive the record, which portion is accessible through an opening 8 in the cover or plate. In the present instance this 5 protecting plate is shown as pivoted upon the rear portion of the frame, as indicated at 9, and can be moved upward when it is desired to gain access to the parts lying beneath the same.
- 10 15 To retain the protecting plate or cover securely in position upon the writing table we have provided it with projections 80 depending on the outer sides of the respective side members and having lips 81 which co- 20 operate with sliding bolts 82 to retain the plate securely in position. The two sliding bolts 82 are preferably connected by arms 83 with a shaft 84 which has mounted thereon a spring 85 tending to move the 25 bolts forward into their operative positions. One end of the shaft is provided with a thumb piece or lever 86 by means of which it may be rotated against the tension of the spring 85 to withdraw the bolts and permit 30 the protecting plate or cover to be raised. Preferably, the forward ends of the bolts are beveled so that they will be automatically retracted when engaged by the depending ends of the projections 80.
- 35 Suitable transfer elements are interposed between the adjacent sheets of paper to transfer the record written upon the upper sheet to the several sheets lying beneath the same. Usually carbon paper is employed 40 for this purpose and is fed from a carbon receptacle 10 across the writing table transversely to the direction of movement of the paper and is interleaved between the adjacent webs of paper.
- 45 As above stated the paper rolls 4 are supported between the side members 1 of the frame upon shafts or spindles 5 which are movably supported in the side members so that they can be withdrawn when it is desired to remove one of the rolls of paper. It is desirable, however, that these shafts or spindles should be locked normally against longitudinal movement so that they will not be accidentally withdrawn and the paper roll displaced inadvertently. As the protecting plate or cover 7 is, in the ordinary use of the machine, raised when it is desired 50 to remove or insert a roll of paper, we have provided means controlled by the movement of this cover plate for locking the shafts against withdrawal while the protecting plate is in its normal position. This lock may be of any suitable character but one very suitable form, which we have embodied in the present machine, consists in pro- 55 viding each of the shafts 5 with an annular groove 87 arranged near one of the side members 1. Slidably mounted on the adjacent side member of the main frame is a locking structure or bar, 88, of irregular 60 shape, having key hole slots 89 arranged adjacent to the respective shafts. The larger portions of these slots are of a diameter equal to or greater than the diameter of the shafts and, when they are in alinement 70 with the shafts, permit the latter to be inserted or withdrawn. The reduced portions of the key hole slots are of a width less than the diameters of the main portions of the shafts and will receive only the reduced portions of the shafts, that is, the portions formed by the grooves 87. When this reduced portion of the key hole slot is in alinement with the shaft it will be obvious 75 that the shaft is locked against longitudinal movement. The movement of this locking bar is controlled by the position of the protecting plate 7. In that form here shown a spring 90 is mounted on one side member of the frame and connected with the structure, 80 which is preferably slidably mounted, and tends to move the same forward or in a direction to move the large portions of the key hole slots in alinement with the shafts and permit the latter to be withdrawn. The 85 bar is provided with an upwardly extending arm 91 arranged in the path of a lip 92 secured to the rear portion of the protecting plate and adapted to engage the arm 91 when the cover is moved from its open to 90 its closed positions and thus move the arm and the locking bar, with which it is connected, rearwardly, thereby automatically locking the shafts or spindles 5 against movement when the cover or protecting 95 plate 7 is in its normal position. When the cover is raised the spring 90 automatically releases the shafts or spindles. 100
- Suitable paper feeding devices are provided for feeding the paper forward over the writing table and means are also provided for actuating these feeding devices through a predetermined distance, thus enabling the length of that portion of the paper which constitutes the bill to be determined in advance and insuring that the paper fed forward will correspond in length exactly to the length of the bill. In the present machine this feeding device comprises what may be termed a paper carriage 110 consisting of two parallel bars 11 and 12 pivotally connected one to the other at one end, as indicated at 13, and provided at their opposite ends with a catch 14 to retain 115 them in their parallel positions. 120
- The bars 11 and 12 of the paper feeding carriage are spaced apart a distance sufficient to receive the forward end of the table top 3 of the frame, which preferably projects a short distance beyond the forward 125 130

edges of the side members thereof. Further, the space between the bars 11 of the paper feeding carriage is sufficient to enable the several webs of paper to be fed between the writing table 3 and the top bar 12. The lower bar 11 is carried by a plate 15 slidably mounted in suitable guideways beneath the top plate 3 of the frame and has secured thereto a longitudinal rack 16 which meshes with a gear 17 rigidly secured to a shaft 18 journaled in the side members of the frame and connected with suitable means for rotating the same. In this manner the carriage is moved away from and toward the paper support or writing table. The paper feeding carriage is provided with suitable paper gripping devices to grip the forward edges of the several webs of paper and cause the same to move forward, that is, in a direction away from the writing table, with the paper feeding carriage. In the present instance this paper gripping device comprises a pair of plungers 19 connected by means of links 20 with crank arms 21 rigidly secured to a shaft 22 extending parallel with the bar 11 and journaled in bearings 23 carried by that bar. These plungers are preferably two in number and are reciprocally mounted in openings 24 formed in the lower bar 11 and have their upper ends pointed and adapted to enter openings 25 in the upper bar 12. Consequently, when the plungers are moved upward the points will pierce the several webs of paper which lie between the two bars and thus firmly connect the same with the paper feeding carriage.

The forward end of the top plate or writing table 3 is provided with slots, as indicated at 26, to permit the passage of the plungers and to permit the movement of the plungers and the paper feeding carriage away from the writing table. These plungers are preferably controlled by the operating device for the shaft 18 which, in turn, controls the movement of the paper feeding carriage. To this end the shaft 22 is provided with a crank arm 27 which is connected by a link 28 with a lug 29 secured to the forward end of the rack 16 which is connected with the bar 15 carrying the paper feeding carriage. The connection between the rack 16 and the bar 15 is preferably a sliding one, the rack being provided on its opposite sides with slots 30 and the bar having lugs 31 adapted to enter these slots. It will be apparent, therefore, that the first movement of the shaft 18 and gear 17 will impart movement to the rack 16 independently of the paper feeding carriage, thus forcing the plungers into engagement with the paper. When the plungers have reached the limit of their movement the further movement of the gear 17 and rack 16 will be transmitted through the plungers to the

paper feeding carriage and in this manner the plungers will be held firmly in engagement with the paper throughout the feeding movement of the carriage.

The means for actuating the shaft 18 and through this shaft the paper feeding carriage and its gripping device preferably comprises a handle 32 mounted on the outer end of the shaft 18. In the present instance the handle is loosely mounted on the end of the shaft and has a pawl 33 arranged to engage a toothed wheel 34 rigidly secured to the shaft 18.

The pawl 33 is preferably a double nose pawl and the teeth of the wheel 34 are so shaped that they may be engaged on either side by the pawl. The pawl is pivotally mounted upon a slide block 35 mounted in a groove 36 formed in the inner face of the handle 32 and is normally held in its innermost position by means of a spring 37 confined between the upper end of the block and a screw 38 mounted on the outer end of the handle, by means of which the tension of the spring may be adjusted.

A V-shaped spring 39 is mounted on the slide block above the pawl and has its fingers extending on opposite sides of the pawl, thus tending to hold the same in engagement with the toothed wheel. When the handle is rotated in a direction to cause the pawl to operatively engage the teeth of the wheel, the wheel and the parts connected therewith will move until resistance is met sufficient to overcome the tension of the spring 37, as when the paper carriage reaches the outer limit of its movement. The further movement of the handle will then cause the pawl to be moved upward against the tension of the spring 37 and the handle allowed to move relatively to the ratchet wheel, thus causing the pawl to reverse and engage the opposite sides of the teeth of the wheel.

As above stated the writing table is hinged at its forward end to the frame. Inasmuch as this table is raised when it is desired to gain access to the paper rolls or other parts that lie beneath the writing table it is desirable that some means should be provided to prevent the paper feeding mechanism moving forward by gravity when the table is so raised. For this purpose we have provided a lug which operates automatically to prevent the movement of the paper feeding carriage by gravity when the writing table is tilted but will not interfere with its operation when the table is in its normal position. While this may be accomplished in various ways we have, in the present instance, provided the lower bar 11 of the carriage with a locking member or lug 93 near one end thereof and have pivotally mounted on the table 3 near the side member of the frame a second locking member or arm 94 having at its forward end a nose 95. This arm is held

normally in its uppermost position by means of a spring 96 and its upward movement is limited by a pin or other suitable stop 97 mounted in the frame member. When the writing table and the arm are in their normal positions the upper end of the nose will lie below the lower edge of the lug on the carriage and will not interfere with the movement of the carriage. When the writing table is tilted and before it has moved far enough to cause the carriage to move outward by gravity the lower edge of the lug 93 will assume a position in the rear of the nose on the arm 94 and the outward movement of the carriage will thus be prevented. The continued pivotal movement of the writing table forces the arm 94 downward against the tension of the spring, which permits the table to have the desired amount of movement and also supports the arm 94 normally in such a position that it will engage the locking member on the carriage before the latter has been tilted to such an extent that the carriage will slide outward by gravity.

The outward movement of the paper carriage may be limited in any suitable manner which will permit of the movement being varied to accommodate the same to bills and checks of different lengths. In the present machine we accomplish this by securing to the longitudinal rack 16 a stop, such as a laterally extending projection 98, and securing to the frame of the machine a second stop 99 which coöperates with the stop on the rack bar to limit the outward movement of the rack bar, this second stop being adjustable. As here shown the second stop 99 is in the form of a block which is secured by a screw to a longitudinal bar 100 having therein a series of screw-threaded holes 101 spaced equal distances apart. By moving the block from one hole to the other the amount of movement which may be imparted to the feed carriage is regulated. As here shown the bar 100 is slidably mounted upon the writing table, for a purpose which will hereinafter appear. It will be understood that when the handle is rotated in a forward direction the carriage will move outward until its movement is positively checked by the coöperating stops. By altering the position of the stop 99 on the bar 100 the movement of the carriage may be adjusted to certain fixed lengths. It is often desirable, however, to make finer adjustments for the purpose, say, of compensating for a slight variation in printed checks or bills. It not infrequently happens that the bills or forms which are printed on the web of paper will vary slightly, may be only a thirty-second of an inch, from the prescribed length.

If the paper carriage moves outward exactly the prescribed length and the length

of the bills varies slightly from the length of the movement of the carriage it will be apparent that after a number of bills have been run off the ends of the bills will be badly out of register with the severing device and, consequently, the severing of the bill will remove a part of the printed matter. To enable the movement of the printing carriage to be adjusted to take care of these slight variations we have provided an auxiliary adjusting device which is operable independently of the stop 99 on the bar 100. This is preferably accomplished by providing means for adjusting the amount of movement of the rack bar 16 relatively to its supporting plate 15 and thus varying the amount of movement of the paper feeding device as a whole. In the present instance the link 28, by means of which the rack is connected with the paper gripping devices is adjustably connected to the paper gripping devices. The connection is preferably made by screw-threading the link and extending the same loosely through a block 111 pivotally supported between the two members of the crank arm 27. Milled nuts 112 and 113 are mounted on the screw-threaded link on opposite sides of the block 111 and by adjusting these nuts the length of the link may be regulated and the relation of the rack to the plate 15 adjusted, it being understood that the movement of the link is positively limited in one direction by the projection 114 which engages the under side of the plate 15 and in the other direction by the plungers 19.

The plungers constituting the paper gripping device are, as above explained, actuated through the medium of the slideable rack bar 16 and, as will be understood, the first movement of the bar to move the paper feeding carriage outward causes the plungers to grip the paper and the first movement of the rack to move the paper feeding carriage rearward, that is, toward the writing table, will move the plungers out of engagement with the paper and permit the carriage to move rearward independently of the paper. It is desirable, however, that these gripping devices should be in engagement with the paper during the writing operation as, in this manner, the paper is held firmly against displacement. To accomplish this the shaft 18 carrying the actuating gear 17 is spring actuated, the spring being so arranged that it will tend normally to move the rack outward. As here illustrated a spring 50 is coiled about the shaft 18 and secured at one end to a fixed part of the machine and at the other end to the shaft. The spring is coiled about the shaft in such a direction that the rotation of the shaft in a direction to move the rack 16 inward will compress the spring. Consequently, when the paper feeding carriage reaches the in-

ward limit of its movement and the shaft 18 is released either by throwing the pawl across its center and thus releasing the ratchet or by the operator releasing the handle, the shaft will be rotated by the spring in a direction to move the rack 16 forward, thus causing the paper gripping devices or plungers to engage the paper the instant the rearward movement of the carriage is completed.

As has been stated the paper gripping devices mounted on the carriage release the paper when the carriage is at the outer limit of its movement and the carriage moves rearwardly independently of the paper. However, in order that the frictional contact between the paper feeding device or carriage and the paper may not tend to move the paper rearwardly and cause the same to buckle upon the writing table it is desirable that other paper gripping devices be supported between the paper feeding carriage and the writing table which will be so actuated as to grip the paper during the return movement of the paper feeding device and release the same during the outward movement of said device. This we accomplish in the present machine by means of two tension fans or gripping devices 51 mounted on a shaft 52 journaled in supporting brackets 53 arranged at opposite sides of the frame near the front of the machine. There are preferably two of these tension fans and they are arranged at points adjacent to the plungers of the paper gripping device on the carriage and each of the tension fans has a slot in its forward edge, as indicated at 54, in Fig. 5, registering with the corresponding slot 26 in the forward edge of the top member or writing table of the main frame, and, consequently, the plunger of the gripping device is free to pass through the tension fan and the latter will engage the paper on both sides of the plunger. Each tension fan has a limited movement relatively to the shaft 52 on which it is mounted. To this end the tubular portion of the fan or gripping device, which is loosely mounted upon the shaft, is provided with a slot 55 extending transversely to the shaft and a lip 56 is rigidly mounted on the shaft, extends through the slot and into a position to engage the fan when the shaft is rotated in a forward direction. By means of this connection the tension fan has movement about the axis of the shaft while the lip 56 is raised, but, when the shaft is rotated forwardly, the lip 56 will engage the body portion of the fan and move the same into engagement with the paper which rests upon the forward edge of the writing table, and so long as the shaft is held in this forward position, the tension fan will have no movement relatively to the shaft, its downward movement being prevented by

the paper on the table and its upward movement being prevented by the lip on the shaft.

A spring 57 coiled about one end of the shaft 52, connected at one end to the bearing bracket 53 and at the other end to the shaft tends normally to rotate the shaft 52 in a forward direction and to cause the paper gripping devices or tension fans to engage the paper and to retain them in engagement therewith.

In order that the paper may move forward freely with the paper feeding device it is desirable that the paper gripping devices or tension fans on the main frame 80 should release the paper before or at the beginning of the outward movement of the paper feeding device. The gripping device may be moved either entirely out of engagement with the paper or its tension may 85 be released sufficiently to permit the movement of the paper. Further, these paper gripping devices should be caused to engage the paper at the beginning of the rearward movement of the paper feeding devices. 90 The paper gripping devices are preferably controlled by the paper feeding device and its operating mechanism. As here shown the shaft 52 has secured to its outer end a plate 58 having two arms, one of which extends downwardly, as indicated at 59, and the other extends forwardly in the direction of movement of the paper feeding carriage, as indicated at 60. Pivotedly mounted on the plate 58 is an arm 61 which extends substantially parallel with the arm 60 and is provided at its forward end and on the inner side thereof with a laterally extending projection or lug 62, the upper wall of which extends substantially parallel with 95 the lower edge of the arm 60 of the plate 58, and will engage said arm when the arm 61 is moved upward, and the lower edge of which is inclined from the forward end of the arm to the rear end thereof, the upper and lower edges of the lug converging to form a point at the rear end thereof. A spring 63 tends to move the pivoted arm 61 upward. A pin 64 projects outwardly from that end of the paper feeding carriage adjacent to the plate 58. When the paper feeding carriage is in its normal position, adjacent to the writing table, the pin 64 will lie in the space between the end of the lug 62 and the inner end of the arm 60. The 100 lug 62 is so arranged with relation to the pin 64 that upon the outward movement of the paper carriage the pin will engage the inclined lower side of the lug 62, thus moving the arm 61 upward and rocking the 105 plate 58 about the axis of the shaft 52, thereby moving the paper gripping devices or tension fans out of engagement with the paper, this movement of the gripping devices taking place at the very beginning of 110 115 120 125 130

the movement of the paper feeding carriage. A catch, such as a pin 65, is mounted in the frame of the machine and a spring 66 tends to move the same outward.

5 When the parts are in their normal positions with the paper feeding carriage adjacent to the writing table the end of the pin will bear against the inner face of the arm 59 of the plate 58. As soon as the forward movement of the carriage has rocked the plate 58 a distance sufficient to relieve the paper gripping devices of the tension of the spring 57, and thus render them inoperative, the pin 65 will be thrown outward by the spring 66 into a position to engage the rear edge of the arm 59 and prevent its return movement, thereby locking the shaft 52 in a position to retain the lip 56 out of engagement with the tension fans and allow the tension fans to move freely on the shaft 52. Obviously, under these circumstances they will exert no material pressure on the paper and will not interfere with its outward movement. Suitable means are provided to move the catch 65 out of the path of the arm 59 and permit the shaft 62 to rotate to move the tension fans into operative engagement with the paper either before the paper feeding device begins its return movement or at the beginning of this movement. In the present instance we have provided means for releasing the shaft at the instant the paper feeding carriage completes its outward movement. To this end the catch or pin 65 is provided in one side thereof with a recess 67, one wall of which is tapered.

Slidably mounted beneath the top plate of the register and arranged in alinement with the recess 67 is a bar 68 having its forward end tapered, as indicated at 69 and arranged to engage the tapered wall of the recess 67. A spring 70 tends to hold this bar normally in its retracted position with its tapered end out of engagement with the wall of the recess. The bar 68 is moved forward to release the tension fans and permit them to grip the paper after the paper feeding carriage has completed its outward movement and before it begins its return movement. In the present instance this movement is controlled by the stop 98 carried by the longitudinally moving rack 16, and, to this end, the slidably mounted stop bar 100 has mounted thereon a laterally projecting finger 103 arranged adjacent to the bar 68. When the stop 98 carried by the rack 16 engages the stop 99 on the stop bar 100 a slight outward movement will be imparted to this rack bar and this movement is sufficient to cause the finger 103 to engage the bar 68 and move the same forward and thus cause it to trip the catch 65 and release the tension fans. The outward movement of the stop bar is positively lim-

ited, preferably by means of the pins 104 which extend through slots 105 in the bar and not only form guides therefor but also positive stops to limit the positive movement of the stop bar and paper feeding carriage. In case it is desired to release the tension fans by hand we have provided means by which this may be accomplished. This means consists of a finger 106 rigidly secured to a sleeve 107 journaled on the shaft 18, and arranged in alinement with the end of the bar 68. The finger 103 terminates near the middle of the end of the bar and the finger 106 is arranged beyond the end of the finger 103. Secured to the other end of the sleeve 107 is an arm 108 having a laterally extending pin or handle 109 which projects through a slot 110 in the side wall of the casing and into a position where it may be readily operated to move the finger 106 into contact with the bar 68. The forward movement of the bar 68 causes the tapered end thereof to engage the inclined wall of the recess in the catch 65 and move the catch out of the path of the arm 59, thereby permitting the shaft 52 to rotate and lock its paper gripping device in engagement with the paper. Upon the return movement of the paper feeding carriage the pin 64 on the end of the carriage will engage the inclined upper edge of the pivoted arm 61 and move this arm downward relatively to the plate 58 and ride over the upper edge of the lug 62 into its normal position.

The operation of the mechanism will be readily understood from the foregoing description and it will be apparent that we have provided automatically actuated means for gripping the paper and retaining the same firmly in position upon the writing table during the writing operating and that this same means is utilized to feed the paper across the writing table and deliver the written bill; also that this gripping means is released at the outer end of the movement of the feeding device to permit the latter to return to its normal position independently of the paper. It will further be apparent that we have provided automatically actuated devices to release and grip the paper upon the outward and return movements, respectively, of the paper feeding device; that both the paper gripping device for the paper feeding carriage and the paper gripping device mounted upon the frame are controlled automatically through the operation of the operating handle; that means are provided for positively limiting the movement of the paper feeding devices in both directions; that this means is adjustable to enable the desired amount of movement to be given to the paper feeding devices and, consequently, a bill of the desired length to be fed from the machine; further, 130

that the operating handle can be moved continuously in one direction, it being capable of further movement after the paper feeding device has reached the limit of its movement; and also that this further movement of the handle reverses the pawl carried thereby and enables the handle to actuate the paper feeding devices in the opposite direction when the movement of the handle 10 has been reversed.

While we have shown and described one embodiment of our invention it will be understood that the same has been chosen for the purposes of illustration only and that 15 we do not desire to be limited to the details of construction shown and described, for obvious modifications will occur to a person skilled in the art.

Having thus described our invention, 20 what we claim as new and desire to secure by Letters Patent is:—

1. In a device of the character described, a paper support, a paper feeding device movable toward and away from said paper support and comprising a paper gripping device, a spring to move said gripping device into engagement with the paper, and means to move said gripping device against the action of said spring to render the same 25 inoperative during the movement of said feeding device toward said paper support, and to release said gripping device to permit the spring to move it into engagement with the paper when said feeding device is 30 moved into a position adjacent to said paper support.

2. In a device of the character described, the combination, with a paper support, a paper feeding device movable toward and 40 away from said support and comprising a paper gripping device, an actuating device operatively connected with said paper gripping device in a manner to first actuate said paper gripping device and then upon the 45 continued movement of the actuating device to actuate the feeding device, of means to automatically impart movement to said actuating device when said paper feeding device has been moved into a position adjacent 50 to said paper support.

3. In a device of the character described, the combination, with a paper support, a paper feeding device movable toward and away from said support and comprising a 55 paper gripping device, an actuating device operatively connected with said paper gripping device, whereby the first movement of said actuating device will actuate said paper gripping device and the further movement 60 of said actuating device in the same direction will actuate said paper feeding device, of a spring operatively connected with said actuating device and tending normally to move said paper gripping device into operative engagement with the paper. 65

4. In a device of the character described, the combination, with a paper support, a paper feeding device movable toward and away from said support and comprising a paper gripping device, an actuating device 70 operatively connected with said paper gripping device, whereby the first movement of said actuating device will actuate said paper gripping device and the further movement of said actuating device in the same direction will actuate said paper feeding device, of a spring operatively connected with said actuating device and tending normally to move said paper gripping device into operative engagement with the paper, an operating member operatively connected with said actuating device, and means for releasing said actuating device from said operating member when the feeding device has been returned to its normal position, thus permitting said spring to actuate said paper gripping device. 75

5. In a device of the character described, the combination, with a frame having a paper support, a paper carriage slidably 80 mounted on said frame, paper gripping devices mounted on said carriage, a rack bar connected with said carriage and having movement relatively thereto, a connection between said rack bar and said paper gripping devices, whereby the first movement of said bar will actuate said paper gripping devices and its further movement in the same direction will actuate said paper feeding carriage, a spring influenced shaft journaled in said frame, and a gear carried by said shaft and meshing with said rack bar, of a handle loosely mounted on said shaft, a toothed wheel rigidly secured to said shaft, and a double pawl pivotally mounted on 85 said handle and adapted to engage said toothed wheel to rotate said shaft in either direction. 95

6. In a device of the character described, a paper support, a paper feeding device 100 movable toward and away from said support and comprising a paper gripping device, a shaft connected with said gripping device to positively operate the same, a spring to rotate said shaft in one direction, 110 and other means to move said shaft in either direction. 115

7. In a device of the character described, a paper support, a paper feeding device 120 movable toward and away from said support and comprising a paper gripping device, a shaft connected with said gripping device to positively operate the same, a spring to move said shaft in one direction, an operating member connected to said shaft 125 to move it against the tension of said spring, and means to release said shaft from said operating member when the feeding device has been returned to its normal position to permit said spring to act. 130

8. In a device of the character described, the combination, with a paper support, a paper feeding device movable toward and away from said support, and actuating mechanism for said paper feeding device, of means to limit the outward movement of said paper feeding device, said means being adjustable to any one of a series of predetermined positions, and other means for regulating the movement of said paper feeding device between said predetermined positions.
9. In a device of the character described, the combination, with a paper support, a paper feeding device movable toward and away from said support, and actuating mechanism for said paper feeding device, of a part carried by said feeding device and having movement relatively thereto, a stop carried thereby, an adjustable stop coöperating with the first-mentioned stop to limit the outward movement of said paper feeding device, and adjustable means for controlling the position of said movable part relatively to said paper feeding device.
10. In a device of the character described, the combination, with a paper support, a paper feeding device movable toward and away from said support, and actuating mechanism for said paper feeding device comprising a rack bar, said rack bar being capable of movement relatively to said paper feeding device, of a stop carried by said rack bar, an adjustable stop coöperating with the stop on said rack bar, and adjustable means for controlling the position of said rack bar relatively to said paper feeding device.
11. In a device of the character described, the combination, with a paper support, a paper feeding device movable toward and away from said support, and actuating mechanism for said paper feeding device comprising a rack bar, said rack bar being capable of movement relatively to said paper feeding device, of a stop carried by said rack bar, an adjustable stop coöperating with the stop on said rack bar, a link extending between said rack bar and said paper feeding device, and adjustable means for connecting said link with said paper feeding device.
12. In a device of the character described, the combination, with a paper support, a paper feeding device movable toward and away from said support and comprising a paper gripping device, an operating arm connected with said paper gripping device, an apertured member supported by said arm, actuating mechanism for said paper feeding device comprising a rack bar, said rack bar being capable of movement relatively to said paper feeding device, of a stop carried by said rack bar, a second stop mounted beneath said paper support to coöperate with the first men-
- tioned stop, said second stop being adjustable to any one of a series of predetermined positions, a screw-threaded link connected with said rack and extending through the apertured member of said feeding mechanism, and nuts mounted on said screw-threaded link on opposite sides of said apertured member.
13. In a device of the character described, the combination with a paper support, a paper feeding device movable toward and away from said support and means to actuate the paper feeding device, of a gripping device supported adjacent to said paper support and fixed against bodily movement with relation thereto, and means controlled by said actuating means to cause said paper gripping device to grip the paper during the movement of said feeding device in one direction and to release the paper during the movement of said device in the other direction.
14. In a device of the character described, the combination, with a paper support, a paper feeding device, and actuating mechanism to move said paper feeding device toward and away from said support, of a paper gripping device fixed against bodily movement with relation to said paper support, a spring tending normally to move said paper gripping device into operative engagement with the paper, and means controlled by the movement of said paper feeding device to compress said spring and render said paper gripping device inoperative.
15. In a device of the character described, the combination, with a paper support, and a paper feeding device movable toward and away from said support, of a paper gripping device, a spring tending normally to move said paper gripping device into operative engagement with the paper, and means actuated by the feeding movement of said paper feeding device to render said paper gripping device inoperative.
16. In a device of the character described, the combination, with a paper support, and a paper feeding device movable toward and away from said support, of a paper gripping device, a spring tending normally to move said paper gripping device into operative engagement with the paper, means controlled by the first portion of the feeding movement of said paper feeding device to compress said spring and render said paper gripping device inoperative, and means controlled by the last portion of the movement of said paper feeding device to release said spring to permit it to move said paper gripping device into operative engagement with the paper.
17. In a device of the character described, the combination, with a frame having a paper support, and a paper feeding device movable toward and away from said paper support.

support, of a shaft journaled on said frame, paper gripping members mounted on said shaft, a spring connected with said shaft and tending normally to move said paper gripping members into engagement with the paper, means for rotating said shaft against the tension of said spring to render said paper gripping members inoperative, means for locking said shaft in a position to retain 10 said spring in its compressed condition, and means for automatically releasing said spring during the last portion of the feeding movement of said paper feeding device.

18. In a device of the character described, 15 the combination, with a frame having a paper support and a paper feeding device movable toward and away from said paper support, of a shaft journaled on said frame, paper gripping members mounted on said 20 shaft, a spring connected with said shaft and tending normally to move said paper gripping members into engagement with the paper, two arms rigidly connected to said shaft, a part carried by said paper feeding 25 device and arranged to engage one of said arms during the first portion of the movement of said paper feeding device, a catch to automatically engage the second of said arms, and means controlled by the movement 30 of said paper feeding device to release said catch during the last portion of the movement of said paper feeding device.

19. In a device of the character described, 35 the combination, with a frame having a paper support and a paper feeding device movable toward and away from said paper support, of a shaft journaled on said frame, paper gripping members mounted on said shaft, a spring connected with said shaft 40 and tending normally to move said paper gripping members into engagement with the paper, a plate rigidly secured to said shaft and having two arms, an arm pivotally mounted on said plate and having a part to engage one of said arms when the pivoted 45 arm is moved upward, said part having its lower edge inclined, a pin carried by said paper feeding device and adapted to engage the inclined part on said pivoted arm and rock the shaft on which the plate is mounted 50 in a direction to render said paper gripping members inoperative, a spring-pressed catch mounted on said frame and adapted to engage one of the arms of said plate when said 55 shaft has been moved to render said paper gripping devices inoperative, said catch having a recess therein, a bar slidably mounted on said frame and having a tapered end portion adapted to enter said recess in said 60 catch, and means controlled in unison with the movement of said paper feeding device to engage said bar and cause the same to move said catch in a direction to release said shaft during the last portion of the movement 65 of said feeding device.

20. In a device of the character described, the combination, with a frame having a paper support, a paper feeding device mounted on said frame and movable toward and away from said paper support, actuating 70 mechanism for said feeding device comprising a shaft, and a handle for actuating said shaft, of a paper gripping device mounted on said frame, a spring tending to move said device into operative engagement with the paper, means actuated by the first portion of the feeding movement of said paper feeding device to compress said spring and render said paper gripping device inoperative, a catch to retain said spring in a compressed condition, a releasing bar to engage 75 said catch and move the same into an inoperative position, thereby releasing said paper gripping device, a finger movably supported adjacent to said bar, and means for causing said finger to engage said releasing bar during the last portion of the movement of said feeding device.

21. In a device of the character described, the combination, with a frame having a paper support, a paper feeding device mounted on said frame and movable toward and away from said support, and actuating mechanism for said paper feeding device, of a paper gripping device mounted on said frame, a spring tending to move said device into operative engagement with said paper, means actuated by the outward movement of said paper feeding device to render said paper gripping device inoperative during 100 the outward movement of said paper feeding device, and means actuated by the movement of said paper feeding device to release said paper gripping device and permit it to engage the paper before said paper feeding device begins its return movement.

22. In a device of the character described, the combination, with a frame having a paper support, a paper feeding device mounted on said frame and movable toward and away from said support, and actuating mechanism for said paper feeding device, of a paper gripping device mounted on said frame, means actuated by said paper feeding device at the beginning of the outward movement thereof to render said paper gripping device inoperative, and means actuated by said paper feeding device as it nears the outer limit of its movement to render said paper gripping device operative.

23. In a device of the character described, the combination, with a frame having a paper support, a paper feeding device mounted on said frame and movable toward and away from said support, and actuating mechanism for said paper feeding device, of a paper gripping device mounted on said frame, a spring tending to move said device into operative engagement with the paper, means to move said paper gripping

device into an inoperative position at the beginning of the outward movement of said paper feeding device, a detent to retain said paper gripping device in its inoperative 5 position, a releasing device to move said detent into an inoperative position and permit said gripping device to move into engagement with the paper, said releasing device being actuated when said paper feeding device is near the outer limit of its movement.

24. In a device of the character described, the combination, with a frame having a paper support, a paper feeding device mounted on said frame and movable toward 15 and away from said support, and actuating mechanism for said paper feeding device, of a paper gripping device mounted on said frame, a spring tending to move said device into operative engagement with the paper, 20 means to move said paper gripping device into an inoperative position at the beginning of the outward movement of said paper feeding device, a detent to retain said paper gripping device in its inoperative position, 25 a trip bar to actuate said detent to release said gripping device, a finger movably mounted near said trip bar, and a part connected with said paper feeding device and adapted to engage said finger to cause it to 30 actuate said trip bar as said feeding device nears the outer limit of its movement.

25. In a device of the character described, the combination, with a frame having a paper support, a paper feeding device mounted on said frame and movable toward 35 and away from said paper support, and actuating mechanism for said paper feeding device comprising a rack, of a paper gripping device mounted on said frame, a 40 spring tending to move said device into operative engagement with the paper, means actuated at the beginning of the feeding movement of said paper feeding device to move said paper gripping device into an inoperative position, a detent to retain said device in an inoperative position, a releasing bar arranged to actuate said detent, a stop bar slidably supported adjacent to said releasing bar, a stop carried thereby, a finger also carried by said stop bar, and a part 45 carried by said rack to engage the stop on said bar as the feeding mechanism approaches the outer limit of its movement, whereby continued movement of said feeding mechanism will move said stop bar to cause the finger carried thereby to engage the releasing bar and actuate said detent to release said paper gripping device.

26. In a device of the character described, 60 the combination, with a frame having a paper support, a paper feeding device mounted on said frame and movable toward and away from said support, and actuating mechanism for said paper feeding device, of 65 a paper gripping device mounted on said

frame, a spring tending to move said device into operative engagement with said paper, means to render said paper gripping device inoperative during the outward movement of said paper feeding device, automatic 70 means to release said spring and permit said paper gripping device to engage the paper before said feeding device begins its return movement, and manually operated means to release said paper gripping device to permit 75 the same to engage the paper.

27. In a device of the character described, the combination, with a frame having a paper support, a paper feeding device mounted on said frame and movable toward 80 and away from said paper support, actuating mechanism for said feeding device comprising a shaft, and a handle for actuating said shaft, of a paper gripping device mounted on said frame, a spring tending to 85 move said gripping device normally into operative engagement with the paper, means actuated by the first portion of the feeding movement of said paper feeding device to compress the spring to render said paper 90 gripping device inoperative, a detent to retain said spring in a compressed condition, a releasing bar to engage said detent and move the same into an inoperative position, means actuated by the last portion of the 95 movement of said feeding device to operate said releasing bar, a sleeve mounted on said shaft, a finger carried by said sleeve and arranged to engage said releasing bar, and manually operated means for rotating said 100 sleeve.

28. In a device of the character described, the combination, with a frame having a paper support, and a paper feeding device carried by said frame and movable toward 105 and away from said paper support, of actuating mechanism for said feeding device comprising a shaft, a toothed member rigidly secured to said shaft, a handle loosely mounted on said shaft, a double nose pawl 110 slidably mounted on said handle and adapted to engage said toothed member to rotate said shaft in either direction, and a spring tending normally to move said pawl toward the inner end of said handle.

29. In a device of the character described, the combination, with a frame having a paper support, a paper feeding device carried by said frame and movable toward and away from said paper support, of actuating mechanism for said feeding device comprising a shaft, a toothed member rigidly secured to said shaft, a handle loosely mounted on said shaft and having a radial guide-way, a slide block mounted in said guide-way, a spring tending to move said slide block toward the inner end of said handle, a double nose pawl pivotally mounted on said slide block, whereby the continued movement of said handle after the move- 125 130

ment of said shaft has been checked will cause said slide block to be moved outward and the nose of said pawl to be swung to the opposite side of said handle, and resilient means to hold said pawl normally in engagement with said toothed member.

30. In a device of the character described, a frame, a paper support hinged at one end to said frame, a paper feeding device movable toward and away from the hinged end of said paper support, and a device to hold said paper feeding device against movement relatively to said paper support when the latter is moved about its hinged connection 10 to said frame.

31. In a device of the character described, a frame, a paper support hinged at one end to said frame, a paper feeding device movable toward and away from the hinged end 20 of said paper support, a finger pivotally mounted on said frame beneath said paper support and having a nose, a spring tending to move said finger toward said paper support, a stop to limit the upward movement of said finger, and a part carried by 25 said paper feeding device and arranged to

be moved into alignment with the nose on said finger when said paper support is moved into an inclined position.

32. In a device of the character described, 30 a frame comprising side members, a paper support, and a cover plate pivotally mounted at one end on said frame, a shaft removably mounted in said frame to support a roll of paper beneath said paper support, said 35 shaft having a groove therein, a locking structure movably mounted on said frame and having a key hole slot, and means actuated by the movement of said cover plate into its normal position to actuate said locking structure to move the reduced portion of 40 said slot into alignment with said shaft, thereby locking said shaft against longitudinal movement.

In testimony whereof, we affix our signatures in presence of two witnesses.

FREDERICK C. NICKOL.
MILTON C. STERN.
